Primary Examiner — Mitchell I. Siegel

(74) Attorney, Agent, or Firm — Hawaii Patent Services;
Nathaniel K. Fedde; Kenton N. Fedde(57) **CLAIM**

The ornamental design for a golf putter grip, as shown and described.

DESCRIPTION

FIG. 1 is a front, left, top perspective view of a golf putter grip;

FIG. 2 is a rear, right, bottom perspective view of the golf putter grip;

FIG. 3 is a front view of the golf putter grip;

FIG. 4 is a rear view of the golf putter grip;

FIG. 5 is a left side view of the golf putter grip;

FIG. 6 is a right side view of the golf putter grip;

FIG. 7 is a top view of the golf putter grip; and,

FIG. 8 is a bottom view of the golf putter grip.

The dashed broken lines in the figures represent portions that form no part of the claimed design. The dot-dash-dot lines, immediately adjacent to the claimed areas in the figures represent the boundaries of the claimed design. None of the broken lines form any part of the claimed design.

1 Claim, 8 Drawing Sheets
